(57) **CLAIM**

The ornamental design for a air vent for a vehicle, as shown and described.

DESCRIPTION

This application is related to the following co-pending applications, of the inventor, filed on even date herewith: Application Ser. No. 29/262,750, entitled “Surface Configuration of a Vehicle, Toy, and/or Other Replicas”; and Application Ser. No. 29/262,792, entitled “Surface Configuration of a Front Portion of a Vehicle, Toy, and/or Other Replicas”.

FIG. 1 is a perspective view of a first embodiment of a air vent for a vehicle according to my novel design; and

FIG. 2 is a front view thereof.

FIG. 3 is a perspective view of a second embodiment of the air vent for a vehicle according to my novel design; and,

FIG. 4 is a front view thereof.

The broken lines are for illustrative purposes only and form no part of the claimed design.
